GOLF CLUB

Bernard Miller, Seattle, Wash.

Application November 8, 1946, Serial No. 708,711

5 Claims. (Cl. 273—77)

1

My invention relates to improvements in a golf club and has particular application to improvement in a putter. As is well known, a person may be putting off line and not be conscious of it. One normally compensates for the fact that the swing is not true by allowing or borrowing one way or another. This is frequently done over long periods of time without knowledge, because it is sometimes difficult to determine that the putter blade is normal to the line of projected flight. Some effort has been made to correct this difficulty by arranging a telltale mark longitudinally of the upper edge of the blade parallel to the face so that a longer and truer indication is observable than merely looking at the top or face of the putter blade. Other efforts have been made to make the head of the putter thick and arranging a telltale mark at right angles with the plane of the face of the blade, and, also, it is common to provide two marks, one parallel to the face of the blade and the other normal thereto. The thickness of the blade is a limiting factor and thus a line of insufficient length is provided to serve as a prolongation of the line of flight normal to the face of the blade.

The object of my invention is to provide a lateral flange extending rearwardly from the face of the blade, which flange is approximately as long as the longitudinal dimension of the putter blade. Said flange carries a telltale mark extending its full length, running from the face of the blade to the trailing edge of said flange. Said telltale mark lies at the middle and intersects the face of the putter blade at this point and with it forms a T so that the plane of the putter blade and the line of flight may easily be indicated.

A further object of my invention is to provide a putter having such a flanged telltale back and a conventional back for the putter, which backs are interchangeable. Thus, in practice, the flanged back with the telltale mark may be used. When the putter is to be used in play, said flanged back may be removed and a conventional back be substituted therefor. Thus, the actual putter may be used both for practice with the telltale mark in place, and in play the one with a conventional back may be used. Said parts are proportioned and arranged, both with regard to weight and balance, so that the replacement of the practice back by the playing or conventional back cannot be detected by the swinging of the club or by the feel thereof. This makes the practicing device of greater value because the swing can be checked without disturbing the feel of the golf club.

2

Further and other details of my invention are hereinafter described with reference to the accompanying drawings, in which:

Fig. 1 is a perspective view of a putter head illustrating the manner in which the practicing device may be secured to the putter head portion, said parts being shown aligned but separated from each other;

Fig. 2 is a similar perspective view of said parts seated one upon the other, the shaft of said golf club being shown foreshortened;

Fig. 3 is a cross-sectional view taken through the line 3—3 in Fig. 2, showing the manner in which a spring-pressed, releasable detent may hold the removable and the fixed portions of said putter head together; and

Fig. 4 is a view similar to Fig. 3 showing the manner in which a conventional back may replace the practice back when said parts are arranged in play.

A golf club embodying my invention comprises a shaft 1, to which is secured to a head portion 2 by the usual hosel 3. Said head portion may be of any conventional shape. For the purpose of illustration, I have shown a blade-type putter. Said head portion is relieved upon its upper edge to define a rear shoulder 4 and a forward shoulder 5. The central or median portion 6 lying between them is narrower than the thickness of said blade and is shorter than the overall length of the putter blade. Extending vertically or transversely of said blade and across the back thereof is a vertical recess 7, the sides of which are tapered so as to provide a pair of dovetailed edges 8. Extending transversely of the central portion 6 are a pair of spring-pressed detents 9 which normally extend beyond the rearward surface of the central portion for the purpose of engaging and holding either of the two removable sections 10 and 11. The removable section 10 has a rearwardly extending lip 12 formed thereon. Upon the upper surface thereof is a telltale line 13 lying normal to the face of the head portion, which also coincides with the forward edge 12a of the lip 12. Said telltale line lies intermediate the ends of said lip and at the middle of the face of the head portion 2.

Said rearwardly extending lip is substantially as long as the length of the putter blade. Thus said telltale line 13 forms a T with the forward edge of the lip 12; and said telltale line would lie upon the line of flight of the ball if the ball were struck by the center of the face of the head portion 2, which is to be desired. Said lip 12 lies at the upper edge of the putting face 2a. It is to

be noted that the shoulder 5 at the forward side of the putting blade is higher than the one at the lower side. This provides a greater width for the face 2a of the head portion so as to assure the ball being struck by the head portion 2, rather than the forward edge 12a of the rearwardly extending lip. Said lip has a forwardly extending flange 14 and a rearwardly extending flange 15 with relation to the plane of head portion 2, which are complementary to the shoulder portions 4 and 5 of the head portion. Thus, as is shown in Figs. 1, 2 and 3, said flanges 14 and 15 fit closely within the shouldered portions 4 and 5 of the head and form therewith smooth, uninterrupted faces both forwardly and rearwardly of the putter blade. The spring-pressed detents fit into apertures 16 in the adjacent face of the rearwardly extending flange 15 and hold said parts together so as to prevent any play or rattle. Said member 10 also has a vertically extending section 17, which is provided with tapered or dovetailed marginal sides so that they will fit within and engage the complementarily formed edges 8 in the head portion 2.

Lying at the end of said section 17 is a boss 18, which lies below the lower edge 2b of the head portion. Said boss preferably is rounded so as to slide easily over the ground, but extends a slight distance beyond said edge so that the removable back may easily be removed from engagement by the detents by striking it on the ground or upon a hard surface, which will force the member 10 upwardly and disengage the latter from the head portion. That is to say, if the putter is arranged with the under surface lying upon the ground or upon a hard surface, the parts may be disengaged merely by exerting pressure on the shaft or by striking said boss 18 upon the ground or upon said hard surface, which will force the member 10 upwardly and the spring-pressed ball detents 9 out of the apertures, respectively, in which said balls seat when the parts are in engagement. Said detents lie substantially equidistant from and at opposite sides of the vertical section 17 and its recess 7 in the head portion. Thus, there are three points of contact: the two spring-pressed detents 9 and the engagement of the dovetailed edges. There is some give in the detents because said balls are urged into frictional engagement with their recesses by coiled springs 9a seated within recesses 9b in said head portion. Said resilient pressure tends to prevent any play from occurring, as well as to prevent the physical disengagement of said parts.

When one wishes to use said putter to determine whether his swing is true, the member 10 is seated upon the head portion of the putter in the manner illustrated in Fig. 2. The lengths of the telltale mark or line 13 provide sufficient visual indication to determine whether or not the putter is being swung so that it moves in a straight path in the line of the projected flight of the golf ball. If the telltale mark tends to move out of alignment or to be oscillated during the putting swing, then the player has visually brought to his attention that his stroke is faulty and he thus can practice until his putting swing is smooth, even and the putting face is always at right angles to the intended course of the golf ball which is to be struck by said face.

It probably would be undesirable to use said putter in actual play, and thus, if desired, said member 10 may be removed and a conventional back portion 11 substituted therefor, as is illustrated in Fig. 4. The section 10 with the rear-

ward extending lip has a disposition of mass and weight comparable to that of the section 11, and thus a player could use either of said sections interchangeably without feeling or sensing the difference. The change may easily be made merely by applying pressure upon the boss 18, as has been described, but said parts will never become loose as long as said detents engage their respective apertures. Also, there is little likelihood of inadvertent detachment of said parts. Because the sections 10 and 11 both straddle the upper edge of the end portion, the latter supports the weight of said sections 10 or 11. The fact that the head is made of two pieces is difficult to discern excepting by looking at the toe of the putter where the parting lines are apparent, as is shown in Fig. 2. To maintain proper balance and weight, I have found it desirable to make the section 10 and the rearwardly extending lip out of some light weight metal such as an aluminum alloy, while the section 11, to produce greater mass and compactness, preferably is made of some heavier metal such as brass, steel or iron. The sections, and particularly the inner-related parts, are made of substantial sections and would thus not become easily damaged so that they would not interfit. If the latter should occur, play might be produced and difficulty of separation or seating the sections 10 or 11 upon the head portion 2. Some slight wear or distortion of said parts might be accommodated because the resiliency of the springs 9a would take up some slight play or unequal engagement or bearing of the parts adjacent the inner-fitting surfaces of the head and the sections 10 and 11.

In several views, I have added detent 9c which seats in a recess in the lower end of the dovetailed slot at the middle of the vertically extending connection 17. It is possible to provide three of these detents to eliminate play, but normally either the pair of detents should be provided to force the back into tight engagement with the dovetailed slots, or the detent 9c should be used alone to shift said vertical section 17 laterally in the dovetailed slot to produce the same result. If they are used alternatively, it provides that one of the legs of said three-point support will bind metal to metal in unyielding abutment. If all three are utilized, it will force all of the opposed faces of the putter blade and the removable back into abutment, and if they are not exactly plane and parallel, it might produce some unevenness, which is undesirable.

I claim:

1. A golf club, comprising a shaft, a partial head secured to said shaft, an elongated striking face on said partial head, a back section mounted removably on said partial head whereby to form a completed head, said back section having a lateral lip extending rearwardly from said striking face, a marking on said lip arranged normally to said striking face for indicating a line of flight from said striking face, spaced flanges on said back section for engaging recesses in said partial head, and detent means resiliently joining said partial head and one of said flanges for holding said parts detachably together.

2. A golf club, comprising a shaft, a partial head secured to said shaft, an elongated striking face on said partial head, the front and back faces of said partial head being recessed longitudinally downward from its upper edge to form shoulders separated by a central longitudinal ridge portion, said back face being recessed transversely between said shoulder and the bottom

edge of said partial head, a back section mounted removably on said partial head whereby to form a completed head, said back section having a lateral lip extending rearwardly from the upper edge of said striking face, a marking on said lip arranged normally to said striking face for indicating the line of flight from said striking face, and spaced flanges on said back section resting upon the spaced shoulders formed in said partial head, a projecting portion of the rearward flange extending through the transverse recess formed in the back face of said partial head, said projecting portion extending slightly beyond the bottom edge of said partial head.

3. A golf club, comprising a shaft, a partial head secured to said shaft, an elongated striking face on said partial head, the front and back faces of said partial head being recessed longitudinally downward from its upper edge to form shoulders separated by a central longitudinal ridge portion, said back face being recessed transversely between said shoulder and the bottom edge of said partial head, the sides of said transverse recess diverging inwardly to form dovetailed edges, at least one detent extending resiliently from the recessed surface of said back face, a back section mounted removably on said partial head whereby to form a completed head, said back section having a lateral lip extending rearwardly from the upper edge of said striking face, a marking on said lip for indicating the line of flight from said striking face, and spaced flanges on said back section resting upon the spaced shoulders formed in said partial head, a projecting portion of the rearward flange having tapered sides extending through the transverse recess formed in the back face of said partial head, said rearward flange having apertures therein registering with said detents for securing the back section detachably to the partial head.

4. A golf club, comprising a shaft, a partial head secured to said shaft, an elongated striking face on said partial head, the front and back faces of said partial head being recessed longitudinally downward from its upper edge to form shoulders separated by a central longitudinal ridge portion, said back face being recessed transversely between said shoulder and the bottom edge of said partial head, a back section mounted

removably on said partial head thereby to form a completed head, said back section having a face overlying the unrecessed portion of the back face of said partial head, spaced flanges on said back section for engaging recesses in said partial head, and detent means joining said partial head and one of said flanges for holding said parts detachably together.

5. A golf club, comprising a shaft, a partial head secured to said shaft, an elongated striking face on said partial head, the front and back faces of said partial head being recessed longitudinally downward from its upper edge to form shoulders separated by a central longitudinal ridge portion, said back face being recessed transversely between said shoulder and the bottom edge of said partial head, the sides of said transverse recess diverging inwardly to form dovetailed edges, at least one detent extending resiliently from the recessed surface of said back face, a back section mounted removably on said partial head whereby to form a completed head, said back section having a face overlying the recessed portion of the back face of said partial head, and spaced flanges on said back section resting upon the spaced shoulders formed in said partial head, a projecting portion of the rearward flange having tapered sides extending through the transverse recess formed in the back face of said partial head, said rearward flange having apertures therein registering with said detents for securing the back section detachably to the partial head.
